APPARATUS FOR MARKING WIRE

Clarence P. Berolzheimer, Chicago Heights, Ill.,
and Karl H. Andren, Milwaukee, Wis.; said
Andren assignor to said Berolzheimer

Application February 11, 1931. Serial No. 515,001

18 Claims. (Cl. 153—1)

The present invention relates in general to improvements in the art of protecting manufacturers against unscrupulous imitation of their products, and relates more specifically to an improved apparatus for applying identifying markers such as metal tabs to wire or other elongated material.

The use of inferior poorly insulated wire in the electrical circuits of buildings is one of the most common of present day fire hazards. Where wire of this type is employed, short-circuiting is in time very likely to occur with the resulting arcing of electrical current, and the dangers attendant therewith. As a precautionary measure the insurance underwriters have established certain requirements as to the properties of the wire used, and as to the degree of insulation, which requirements must be met by the owner of a building who desires to obtain fire insurance upon his property. Under present day practice, however, it is very difficult for the average individual who purchases odd lots of wire to ascertain whether or not wire which has been obtained meets the required standards, and this makes it possible for unscrupulous manufacturers to offer to the public products of inferior quality.

It is therefore one of the objects of this invention to provide new and useful apparatus for facilitating the application of identifying markers or tabs to wire or other elongated articles.

A more specific object of the invention is to provide an improved apparatus which is arranged to advance the wire longitudinally and to affix identifying markers or tabs to the wire while it is being advanced.

Another specific object of the invention is to provide an improved apparatus for marking wire which is adapted to apply the tabs and markers at fixed, equally spaced intervals upon the wire.

Still another specific object of the invention is to provide an apparatus in which the wire to be marked is fed over a rotor and in which said rotor is provided with mechanism for automatically affixing a tab or marker to the wire at each revolution of the rotor, or at other definite intervals.

Other objects of the invention reside in the provision of an improved apparatus for marking wire which is adapted to firmly affix the markers to the wire, to carry out the operation in an expeditious manner, and to otherwise efficiently produce the desired result.

With the above and other objects in view, the invention consists of the improved apparatus for marking wire, and all its parts and combinations, as set forth in the claims, and all equivalents thereof.

In the accompanying drawings illustrating one complete embodiment of the preferred form of the invention, in which the same reference numerals designate the same parts in all of the views:

Fig. 1 is a front elevational view of the improved apparatus;

Fig. 2 is a part sectional view taken on line 2—2 of Fig. 1, parts being broken away;

Fig. 3 is an enlarged sectional view taken on line 3—3 of Fig. 1;

Fig. 4 is a sectional view taken on line 4—4 of Fig. 3;

Fig. 5 is an enlarged fragmentary sectional view showing the slide in a position just after it has bent the end of the metal strip over the wire;

Fig. 6 is a similar view showing the slide in its extreme position of advancement after the strip has been severed and completely bent around the wire;

Fig. 7 is an enlarged fragmentary detail view taken on line 7—7 of Fig. 1;

Fig. 8 is an enlarged sectional detail view taken on line 8—8 of Fig. 1; and

Fig. 9 is a fragmentary plan view of a portion of the rotor showing the raised plate thereon.

Referring to the drawings, the numeral 10 designates a suitable supporting platform having mounted thereon a supporting portion 11 provided with an upright housing 12. An electric motor 13 which depends from a suitable support secured to the lower side of the platform top is connected by means of an endless belt 14 with a pulley 15 mounted on one end of a horizontally extending shaft 16, said shaft being journaled through the lower portion of the housing 12. The other end of the shaft 16 carries a rigidly mounted pulley 17 and an intermediate portion of said shaft carries a worm 18.

The worm 18 engages a worm wheel 19 mounted rigidly on a shaft 20, the latter being journaled at right angles to the shaft 16 in a bearing 21 and in a bearing 22 in the housing 12. The inner end of the shaft 20 has rigidly mounted thereon a rotor 23 (see Fig. 3), said rotor having its rear wall formed with a circular opening which surrounds a circular plate 24 carried by the side of the housing 12, said plate being formed with a substantially oval cam groove 25 therein.

Extending toward the front of the rotor is a support 26, through which a pin 27 extends, said pin supporting a reel 28 for carrying in rolled form an elongated strip of metal 29 or other material to be used for marking the wire.

100

105

110

5   Mounted in a slot 30 formed in the rotor 23 are slidable blocks 31 and 32, one of said blocks being movable on one side of the shaft 20 and the other block being movable on the other side thereof. The said blocks have extending rearwardly therefrom rods 33 and 34 respectively on the ends of which are mounted rollers 35 and 36 which ride in the cam groove 25 of the stationary circular plate 24. It may thus be seen that 10 upon revolution of the rotor 23 that the slidable blocks 31 and 32 will be moved back and forth in the slot 30 due to the engagement of the rollers 35 and 36 with the cam groove 25.

15   The block 31 has pivotally secured thereto one end of a link 37. The other end of said link is pivoted to an extension 38 of a member 39 which loosely surrounds a short shaft 40 journaled in a bearing 41. The said member 39 is provided with another extension 42 which carries a yieldingly and pivotally mounted dog 43 (see Figs. 7 and 8). The said dog is engageable with a ratchet wheel 44 which is fixed to the shaft 40. The shaft 40 also carries a fixed roller 40' and a fixed gear 45 in front of said roller. The gear 20 45 meshes with another gear 46 mounted on a shaft 47 extending parallel to the shaft 40. The shaft 47 carries a fixed roller 48 which acts in conjunction with the roller 40' on the shaft 40 to feed the strip 29 therebetween. The shaft 47 is 25 journaled in a bearing member 49 depending from a yieldingly mounted trigger controlled slide 50. The said slide is movable on a pin 51 extending through a longitudinal bore thereof, the inner end of said pin being fixed to a portion of the rotor and the outer end having a coil spring 51' extending therearound. By moving the trigger 52' outwardly to move the slide on the pin against the tension of the coil spring 51', the rollers for feeding the strip 29 may be slightly 30 separated from one another to permit the ready insertion of the strip of material therebetween when the device is being prepared for operation. An extension 51 from the bearing 41 carries a yieldingly pivoted dog 52 which also engages the 35 ratchet wheel 44.

40   From the above it may be seen that when the link 37 is pulled downwardly by slidable movement of the block 31, that there will be a pull upon the extension 38 and a partial rotation of the member 39 on the shaft 40. Due to the fact that the extension 42 is integral with the member 39 the dog 43 carried thereby will cause turning of the ratchet wheel 44 and also 45 turning of the shaft 40 to which said ratchet wheel is affixed. This in turn will cause rotation of the roller 40' on the shaft 40, and through the gears 45 and 46 simultaneous rotation of the roller 48 on the shaft 47 and feeding of a 50 definite length of the strip 29 outwardly to the position shown in Fig. 3. When the slidable block 31 is moved in the other direction, the dog 43 will slip over the teeth of the ratchet wheel 44 and said ratchet wheel will at the same time be kept from rotation by the engagement of the 55 other dog 52 therewith.

55   The strip of material will be guided upwardly between a channel-shaped guiding member 53 and a complementary guiding member 54 which fits within the channel 53. The guide 54 is suitably connected with the slide 50, so that when the trigger 52' is moved outwardly to separate the rollers, the guides 53 and 54 are also separated to facilitate threading of the strip 29 therethrough.

60   The slidable block 32 is provided with a recess

55 therein which is engaged by one end of a bell crank 56. The latter is pivoted to the rotor as at 57 and has its other end pivoted as at 58 to one end of a link 59. The other end of the link is pivotally connected to the end of an adjustment member 60 which is threaded in the outer end of a slide 61. The slide 61 is movable in a slot 62 which extends transversely through the rotor near the periphery thereof. The inner end of the slide has its lower surface formed with a recessed portion 63 and with a cutting edge 64. Supported by the rotor near the slide 61 are adjustably mounted guiding fingers 65 which extend inwardly at an angle.

65   The periphery of the rotor near the front thereof is formed with a pair of spaced apart grooves 66 and 67 for receiving the wire or cord which is to be marked. The groove 66 curves nearer to the groove 67 at a point on the periphery adjacent the slide 61 as shown in Fig. 4 and at this point the groove guides the wire to position in a tool 68, said tool having a substantially semi-circular recess 69 formed on the inner edge thereof.

70   Upon rotation of the rotor, and movement of the block 32 due to the action of the roller 36 in the cam groove 25, the bell crank lever 56 will be rocked and through the link connection 58 will cause outward movement of the slide 61 from the position shown in Fig. 3. When said slide has moved half way out it will assume the position shown in Fig. 5, having bent the upper end of the strip 29 over the cord 70. Upon further movement the knife edge 64 of the slide will sever the strip of material 29 and through the cooperation of the recess 63 in the slide 61 and the recess 69 in the tool 68 will cause a clamping of the strip around the cord, as shown in Fig. 6. The slide will then withdraw, after which a new length of the strip 29 is projected from the strip guides.

75   The pulley 17 on an end of the shaft 16 is connected by means of an endless belt 71 with a pulley 72 mounted on a lower shaft 73. The latter shaft carries a rigidly mounted gear 74 which 80 meshes with a gear 75 mounted on another shaft 76 for carrying a winding reel 77. The shaft 76 is journaled in bearings 78 and is removably held in position in said bearings by slidable keys 79. The winding reel is connected to the shaft so as 85 to be driven by the same through a pin 80 on an arm 81, said pin engaging an aperture in a side of the reel.

90   Another shaft 82, journaled in bearings 83 in alignment with the shaft 76 carries a reel 84 containing the wire or cord which is to be marked. The shaft 82 is also removably held in the bearings by means of keys 85 similar to the keys 79. The inner end of the shaft 82 carries a fixed brake drum 86 which is normally yieldingly engaged by 95 a pivoted drag member 87 to retard the rotation of the shaft 82.

95   The shaft 73 also carries a fixed pulley 88 which is connected by an endless belt 89 with another pulley 90 mounted rigidly on a shaft 91. The 100 said shaft has formed thereon a reversing screw 92 which when rotated is capable of moving a guiding member 93 back and forth. The said guide is provided with an extension 95 having a bifurcated end 96 which engages and rides back 105 and forth along a shaft 97.

110   The cord 70 which is to be marked is unwound from the reel 84, passed behind a guiding pulley 98, around the upper portion of the rotor in the inner grooves 66, around a pulley 99, again around 115

the rotor in the outer groove 67, in front of a guide pulley 100, around the reciprocating guide 93 to the winding reel 77.

Pivotedly mounted on the upper end of the housing 12 is an arm 101 carrying on its outer end rollers 102, which rollers have pliable peripheries normally engageable with the cord or wire positioned in the outer groove 67 of the rotor to firmly press the tabs which have been affixed to the wire in position. The arm 101 also has extending therethrough near its outer end a shaft 103 carrying a crank 104 at one end and having its other end connectable through an arm 105 with one end of a link 106. The other end of the link is pivotally connected to an extension 107 of the housing 12. By rotation of the crank 104, the rollers 102 can be readily moved to disengaged position when a wire or cord is being originally threaded through the machine. The periphery 20 of the rotor is also provided with a raised grooved plate 108 which extends over the outer groove 67 and over which the wire or cord extends. This plate is adapted to cooperate with the rollers 102 in causing pressing of the markers firmly on the wire.

In operation, when the rotor 13 is set in motion, the wire 70 having been previously threaded through the apparatus in the manner heretofore described, said wire will be unwound from the reel 84 and will be drawn by the revolving rotor around the inner groove 66 thereof. When the rotor is in the position shown in Fig. 1, the movement of the block 32, through the action of the roller 37 in the cam groove 25, will cause the slide 61 to move from the position shown in Fig. 3 to the position shown in Fig. 6, severing the end of the strip 29 and wrapping the same around the cord. When this operation has been completed, and as the rotor continues to revolve, the action of the other block 31, through the engagement of the roller 35 with the cam groove 25 will act through the link 37 to cause rotation of the strip feeding rollers and advancement of the strip to again extend the end thereof read for the next cutting and clamping operation.

It will thus be seen that upon each revolution of the rotor one marker or tab will be affixed to the wire, and that said markers will be affixed at standard intervals which correspond in length with the circumference of the rotor. The portion of the wire to which the tabs have been affixed then passes around the pulley 99 and back to the rotor around the outer groove 67 thereof. As this portion of the wire is carried around by rotation of the rotor it will be engaged between the plate 108 and the pressing rollers 102 to cause additional pressing of the tabs in position. The marked wire will then pass from the outer groove of the rotor in front of the pulley 100 and around the guide 93 to the winding reel. Due to the action of the reversing screw 92, the guide 93 will be reciprocated back and forth to cause an even winding of the marked wire upon the winding reel.

The drag 87 engaging the brake drum 86 retards the unwinding of the reel 84 and prevents the formation of slack in the wire. The belt 71 which through the pulley 72, shaft 73, and gears 74 and 75 drives the winding reel is so adjusted that it can slip while imparting rotation to the pulley 72. This slipping is necessary in order to compensate for the varying diameter of the winding reel as the wire is wound thereon.

It is preferred to use a strip of metal for marking the wire, but it is to be understood that any

other suitable material may be employed. It is also to be understood that the improved apparatus may be utilized advantageously in marking any other elongated article of manufacture other than the wire or cord shown and described, and various other changes and modifications may be made in the apparatus without departing from the spirit of the invention as set forth in the annexed claims.

It is claimed and desired to secure by Letters Patent:

1. In combination, a rotor, means for guiding a longitudinally advancing wire over a portion of said rotor and again around the rotor in a position laterally spaced from the first position, means for initially clamping a marker about said wire in its first position on the rotor, and other means engageable with the wire in its second position on the rotor for additionally pressing the marker on the wire.

2. In combination, a rotor, a pulley spaced from said rotor, means for guiding a longitudinally advancing wire over a portion of said rotor, around said pulley and again over a portion of the rotor in a position laterally spaced from its first position thereon, and means for clamping markers about said wire as it passes over the rotor, said guiding means for the wire serving to maintain the proper tension during the clamping operation.

3. In combination, a rotor, a pulley spaced from said rotor, means for guiding a longitudinally advancing wire over a portion of said rotor, around said pulley and again over a portion of the rotor in a position laterally spaced from its first position, means for initially clamping a marker about said wire in its first position on the rotor, and other means engageable with the wire in its second position on the rotor for additionally pressing the markers on the wire.

4. In combination, a rotor engageable with a longitudinally advancing wire, means for initially clamping markers about said wire as it passes over the rotor, a roller engageable with the wire after it has been marked, and means on the rotor cooperable with said roller in additionally pressing the markers on the wire.

5. In combination, a movable member engageable with a longitudinally advancing wire, means for initially clamping markers about said wire as it is engaged by said movable member, anti-friction means engageable with the wire after it has been marked, and means on the movable member cooperable with said anti-friction means in additionally pressing the markers on the wire.

6. In combination, a rotor engageable with a longitudinally advancing wire, means for initially clamping a marker about said wire as it passes over said rotor, a roller engageable with the wire after it has been marked for additionally pressing the markers on the wire, and means for moving said roller out of engaging position.

7. In combination, a movable member engageable with a longitudinally advancing wire, means for initially clamping a marker about said wire as it is engaged by said movable member, anti-friction means engageable with the wire while still engaged by said movable member for additionally pressing the markers thereon, and means for moving said anti-friction means out of engaging position.

8. A wire marking apparatus comprising a rotatable reel for wire to be marked, a reel on which wire from said first reel is adapted to be wound,

80

85

90

95

100

means interposed between said two reels over which the wire is advanced for clamping markers at intervals thereon, and means for transmitting motion to said winding reel including a pulley and a driving belt, said belt being adjusted to provide for slippage on the pulley to compensate for the varying diameter of the winding reel as the wire is wound thereon.

9. In combination, a rotor engageable with a longitudinally advancing wire, means carried by said rotor for clamping a marker about said wire during revolution of the rotor, means for feeding marking material to said clamping means, actuating mechanism for said clamping means, actuating mechanism for said feeding means, and a common means for imparting movement to said two actuating mechanisms.

10. In combination, a movable member engageable with a longitudinally advancing wire, means cooperable with said movable member for initially and finally clamping a marker about said wire while said movable member is engaged therewith, means for feeding marking material to said clamping means, actuating mechanism for said clamping means, actuating mechanism for said feeding means, and a common means for imparting movement to said two actuating mechanisms.

11. In combination, a pair of relatively fixed and movable supporting members, one of said members having a cam groove therein and the other of said members being engageable with a longitudinally advancing wire, means carried by said latter member for clamping markers about said wire, means for feeding marking material to said clamping means, and actuating mechanism for said clamping means and for said feeding means engageable with said cam groove of the first mentioned supporting member.

12. In combination, a fixed supporting member having a cam groove therein, a rotor revolvably mounted on said support and engageable with a longitudinally advancing wire, means carried by said rotor for clamping a marker about said wire during revolution of the motor, means for feeding marking material to said clamping means, and actuating mechanism for said clamping means and for said feeding means engageable with said cam groove of the support and driven thereby during revolution of the rotor.

13. In combination, a fixed supporting member having a cam groove therein, a rotor revolvably mounted on said supporting member and engageable with a longitudinally advancing wire, said rotor having a slot therein, means carried by the

rotor for clamping a marker about said wire during revolution of the rotor, means for feeding marking material to said clamping means, a pair of blocks slidable in the slot of said rotor, a cam follower carried by each block and engageable with the cam groove of the support, and means between said slideable blocks and the clamping and feeding means for actuating the latter during revolution of the rotor.

14. In combination, a movable member engageable with a longitudinally advancing wire, means carried by said movable member for initially clamping a marker about said wire while travelling longitudinally about said member, and anti-friction means engageable with the wire while still coating with said movable member for subsequently additionally pressing the markers thereon.

15. In combination, a rotor engageable with a longitudinally advancing wire, means carried by said rotor for initially clamping a metallic marker about said wire during each revolution of said rotor, and other means independent of said clamping means engageable with the wire after it has been marked for additionally pressing the markers on the wire.

16. In combination, a fixed supporting member having a cam groove therein, a rotor revolvably mounted on said support and engageable with a longitudinally advancing wire, means carried by said rotor for clamping a marker about said wire during each revolution of the rotor, means for feeding marking material to said clamping means, and actuating mechanism for said clamping means and for said feeding means engageable with said cam groove of the support and driven thereby during revolution of the rotor.

17. In combination, a rotor peripherally engageable with a wire while in motion, means carried by said rotor for initially clamping a marker about the wire while travelling around said rotor, and other means cooperable with said rotor for subsequently further clamping the marker on the wire.

18. In combination, a movable member engageable with a wire while in motion, means carried by said movable member for initially pressing a marker against the wire while travelling longitudinally about said member, and other means cooperable directly with said movable member for subsequently further pressing the marker against the wire.
